United States Patent Office

Des. 221,837
Patented Sept. 14, 1971

221,837

SPOON-SHAPED PACKAGE ELEMENT FOR FOOD OR THE LIKE

William E. R. Watt, New Kensington, and Regis A. Fleck,
Tarentum, Pa., assignors to Aluminum Company of
America, Pittsburgh, Pa.

Filed Oct. 25, 1968, Ser. No. 14,184

Term of patent 14 years

Int. Cl. D9—99

U.S. Cl. D9—185

FIG. 1.

FIG. 2.

FIG. 3.

FIG. 1 is a top plan view of a spoon-shaped package element for food or the like.

FIG. 2 is a side elevational view thereof.

FIG. 3 is an enlarged cross-sectional view thereof taken along line III—III of FIG. 1.

We claim:

The ornamental design for a spoon-shaped package element for food or the like, substantially as shown.
